UNITED STATES PATENT OFFICE.

STEPHEN W. WOOD, OF CORNWALL, NEW YORK.

IMPROVEMENT IN MACHINES FOR PATCHING BULLETS.

Specification forming part of Letters Patent No. 136,352, dated February 25, 1873.

To all whom it may concern:

Be it known that I, STEPHEN W. WOOD, of Cornwall, county of Orange and State of New York, have invented a new Machine for and Process of Patching Bullets; and I do hereby declare that the following is a full, clear, and exact description thereof, reference being had to the annexed drawing making part of this specification—

Figure 1 being a side elevation of the machine, with the table for holding the material with which the bullets are to be patched removed; Fig. 2, a vertical cross-section thereof through the line xx of Fig. 1; Fig. 3, a plan of two of the rollers and feed-bar detached, and representing bullets, respectively, in position before, while, and after being patched; Fig. 4, a detached view of the opening and closing jaws for gathering or folding the patch over or around the end of the bullet, with a sectional view, in part, of the rollers. Figs. 5, 5' are also detached views of the guides for directing the patch around the bullet, with a sectional view, in part, of the rollers. Figs. 6, 7, 8 are views of several modifications of devices by which the patch may be gathered or folded over or around the bullet; Fig. 9, a plan of the two lower rollers, with a device for moistening the bullet to receive the patch; Fig. 10, a vertical cross-section, showing the same device as in Fig. 9; Fig. 11, a plan of the lower rollers and a device for moistening the patch before it is wrapped around the bullet; Fig. 12, a vertical cross-section, showing the same device as in Fig. 11.

My invention consists, first, in automatically wrapping a patch around a bullet by means of rollers and guide, in the manner hereinafter described; second, in mechanism for automatically wrapping a patch around a bullet and folding or gathering the same over or around the end thereof, substantially in the manner herein set forth; third, in the combination of elements for first patching or wrapping a patch around a bullet and subsequently moistening the patch; fourth, in devices for moistening or partially moistening with water or any suitable glutinous substance the bullet, so that the patch may adhere thereto and be carried around with the bullet, substantially in the manner and for the purpose herein specified; fifth, in the arrangement of a series of

rollers, so constructed as to admit the bullet to be patched, and to yield, by their elasticity, or adjust themselves thereto, and to release the same, substantially as herein described; sixth, a circular guide for directing the patch around the bullet, in conjunction with a series of rollers, or their equivalents, constructed and arranged substantially in the manner herein set forth.

A in the accompanying drawing represents a frame, upon which are mounted the various working parts constituting the machine proper. B B are rollers placed at the required distance apart, upon which the bullet to be patched is placed. C is an upper roller, movable and self-adjusting, which is first raised to admit the bullet to the position to receive the patch, and is then lowered, resting upon the upper side thereof, embracing the bullet between the three rollers. The bullet R now being in position, as shown in Figs. 2 and 3, proper motion is given to the rollers B B and C by means of cog-wheels G G and H, turning the bullet in the direction indicated by the arrow. The patch to be wrapped around the bullet is now fed through a guide, I, secured to the table J, and its end presented to the point of contact between the surface of the bullet and face of the roller C. To direct the end of this patch so that it shall follow and be wrapped around the bullet as it rotates by means of the rollers B B and C, a guide, K, is placed between the rollers B B and C in grooves $c' c$, and secured to the bed of the frame A. This guide K is placed centrally between the rollers B B and C, and its inner periphery e is tangent to, or nearly so, to the surface of these rollers, so that the bullet, when placed upon the two lower rollers and moved forward by the sliding bar W, may pass into this circular guide K, and remain therein until patched, the inner periphery e directing the patch around the bullet, and the three rollers conjointly, wrapping the patch tightly around its surface. The bullet now having its patch wrapped around it with a sufficient portion of the patch extending over the end thereof, the adjustable jaws O are caused to approach each other, thereby folding or gathering the extending end over and around the end of the bullet, as shown in Fig. 3, position 2. These adjustable jaws O are placed in the grooves $c' c$ (the first

series) formed in the several rollers, and through which the bullet passes in its movement forward to position 2, encircling the patch immediately in rear of the end of the bullet. These adjustable jaws O are pivoted at s , and closed to gather or fold the patch over or around the end of the bullet by means of a cam, t , and opened to permit the succeeding bullet to pass through by means of a spring or rubber, u , secured to the lower arms p ; or they may be operated by any equivalent means. Small indentations r are formed in the inner faces of the jaws, centrally, so that the gathered end of the patch may extend through between them; or the inner faces x may be plain, so as to flatten the patch upon the end of the bullet after being gathered around it.

To retain the bullet in position, and to prevent the patch slipping forward while being folded or gathered over its end, grooves d are formed in the rollers, as shown in Fig. 1, and a stop, P , may be secured to the movable roller, against which the front end of the bullet may bear, and which is raised, with the roller C , to allow the patched bullet to move forward, as shown in dotted lines. A second stop, P' , is also secured to the roller C , which retains the patched bullet in position while being moistened to shrink the patch thereon.

The bullet now having received its patch, the upper roller C is raised, when the feed-bar W moves forward, presenting another bullet to the guide K in position to receive its patch, and the preceding patched bullet being moved forward at the same time to position 3, Fig. 3, to be moistened in any convenient manner, and then delivered from between the rollers by the third preceding bullet being moved forward to receive its patch.

One practical method of moistening the patch is represented in Fig. 5—viz., by immersing or partially immersing division n of the sectional rollers B in water or suitable glutinous substance, which, in their revolution, will sufficiently dampen the patch.

To prevent the patch being moistened (by the patched bullet) so as to adhere to the rollers in the act of being wrapped around the bullet, grooves i are formed in these rollers, so as to disconnect and separate the moistened section or division n from the division m , by which the patch is wrapped around the bullet.

When the bullet is to be moistened by water or any suitable glutinous substance, that the patch may adhere thereto while being wrapped around, a wheel, b , Fig. 10, is placed in the grooves c and pressed against the bullet, instead of or in conjunction with the guide K , its lower edge or an intermediate roller, D , being immersed in the liquid to be used, and when rotated by means of the friction of the bullet, turned by the rollers B and C or otherwise, a narrow belt of moisture is laid around

the bullet to which the patch adheres, thus carrying it around with and securing it to the surface of the bullet.

A strip of moisture by water or glue may be rolled or laid upon the lower surface of the patch, as in Fig. 11, if preferred, instead of moistening the bullet.

Guide-rollers g may be employed to direct the patch around the bullet instead of the circular guide K , if preferred.

It is evident that a greater number of rollers might be used if desired, and that various modifications in mechanism for folding or gathering the patch over or around the end of the bullet might be substituted in place of the adjustable jaws O , some of which are represented in the accompanying drawing, Fig. 6—being rollers m m' moving laterally or at right angles to the end of the bullet. This figure represents the rollers in position previous to and after having gathered or folded the patch over or around the bullet.

Fig. 7 are two conical rollers to perform the same office.

Fig. 8 represents a coiled wire, which surrounds the patch, and to fold or gather it around the bullet is drawn laterally to the bullet through guide-pins f , thereby gradually closing the end of the patch, as in Figs. 2 and 4.

What I claim as my invention, and desire to secure by Letters Patent, is—

1. Combined with rollers for wrapping a patch around a bullet, substantially in the manner herein set forth, folding-jaws for automatically folding, gathering, or closing the patch over or around the end of the bullet, in the manner described.

2. The method, substantially as shown and described, of first patching or wrapping a patch around a bullet by mechanism as herein set forth, and subsequently moistening the same, substantially as and for the purpose herein specified.

3. The combination of parts herein shown and described for patching a bullet, with mechanism for moistening or partially moistening with water or any glutinous substance the patch or bullet, substantially as and for the purpose herein specified.

4. A series of rollers for patching bullets, which are movable and adjustable, constructed and combined for operation substantially as herein set forth.

5. A series of sectional rollers, adapted for receiving the additional devices shown for patching bullets, substantially as and for the purpose herein specified.

6. A guide, in combination with a series of rollers for directing the patch around the bullet, constructed and arranged substantially as herein described.

STEPHEN W. WOOD.
